FIG-7.

UNITED STATES PATENT OFFICE

FREDERICK K. FILDES, OF ALTOONA, PENNSYLVANIA

SHEET-METAL CONTAINER

Application filed October 28, 1930. Serial No. 491,799.

This invention relates to sheet metal containers of the kind used on railway cars and automobile trucks for the shipment of fractional car load lots of goods and merchandise.

Containers of this character are used in the open, being carried in exposed positions on flat bottom freight cars and trucks, a plurality of the containers spaced side by side forming a car or truck load. The containers, therefore, are subjected to all kinds of weather and are also at times easily accessible to unauthorized persons. It is essential, therefore, that the container be weatherproof and that its door locking mechanism be effective. Moreover, the door opening of the container should be high and wide to facilitate loading and unloading and to adapt the container for carrying large articles, but the door should be capable of being swung open and closed within a relatively narrow space, since it is often desirable to open the container when the space provided for swinging the door outwardly is very limited, as, for example, when the container is on a car standing alongside a loading platform, or when the car is alongside another car on an adjacent track.

The present invention therefore has for its object to provide a container having a wide door opening and a door therefor composed of two leaves hinged respectively to the sides of the door frame, each leaf consisting of a plurality of sections foldable on axes parallel to the hinge axes, so that the door can be swung open in a relatively narrow space; to provide simple but effective locking mechanism for the door; to provide simple and efficient water-proof packing between the edges of the door leaves and the door frame and between the meeting edges of the leaf sections; to provide a door made of foldable sections in which the sections are of hollow sheet metal construction presenting a plane smooth inner surface with no projecting parts likely to cause damage to goods housed by the container and locking mechanism for the sections completely housed therein; and to provide other improvements in containers of this type, as will hereinafter appear.

In the accompanying drawings:—

Fig. 1 is a front elevation of a door embodying the present improvements;

Fig. 2 is a vertical section taken on line 2—2 of Fig. 1;

Fig. 3 is a detail vertical section on line 3—3 of Fig. 1;

Figs. 4, 5 and 6 are horizontal detail sections taken on the corresponding lines of Fig. 1;

Fig. 7 is a vertical section on line 7—7 of Fig. 2;

Fig. 8 is a horizontal section through the lock operating lever taken on the line 8—8 of Fig. 1; and

Figs. 9 and 10 are detail views illustrating a locking bolt and the method of mounting and operating the same.

The container, only fragments of which are shown, is formed with a wide door opening in one or, preferably, both sides and with a hinged double door closing this opening. According to the present invention, this door consists of two leaves secured by hinges 10 to vertical angle bars 11 which form the sides of the door frame. Each leaf comprises a pair of sections, A, B, A', B' connected by hinges 12 so that the sections of a pair can be folded to lie with their outer faces opposed. Hinges 10 are preferably double hinges, consisting of two leaves secured respectively to the frame and the door section and an intermediate, or link, member pivoted to the leaves by pintles 13 and 14. It will be observed that sections A, A' are somewhat narrower than sections B, B', so that when the former are turned to lie against the faces of the latter, the free edges of the former will lie slightly to the inside the axes of pintles 13 and the latter can then be turned about the axes of the pintles to bring the inner faces of sections A, A' substantially flush against the side of the container, leaving a clear opening between the frame bars 11 with no parts of the door projecting therein to interfere with the loading and discharge of the container.

The door sections are of hollow sheet metal construction. Each section is built up of an inner one-piece member of vertically elongated

gated shallow trough-like form having a plane body 16, sides and ends 17 bent at right angles to the body and a bordering flange 18 in a plane parallel to the body, and an outer 5 one-piece sheet 19 disposed over flange 18 and having its edges bent around and overlapping the same. Outer sheet 19 is cut away and bent to form upper and lower sunken portions, or panels, 20 and 21, the side and 10 end walls 22 of which are respectively parallel to and spaced from the sides and ends 17 of the inner member, these walls terminating in right angular flanges 23 which rest flat against the body 16 of the inner member 15 and are secured thereto by welding.

One of the objects of the invention is the provision of simple and effective means for rendering the door weather-proof. The means for attaining this object comprises 20 soft rubber strips folded longitudinally and having overlapped edges secured to the edges of the door sections and adapted when the door is closed to press against rigid abutments on opposing sections and on the door 25 frame. Thus Fig. 3, which is a vertical section through the upper edge of section B' and the adjacent top portion of the container, shows a rubber strip 23 longitudinally folded and having overlapping edges secured between a backing strip 24 and the flange of 30 the door section by means of screws 25. Due to the resiliency of the rubber, the free portion of this strip is substantially cylindrical when not under pressure, but when the door 35 is closed the strip is pressed between the flange of the door section and the edge of a plate 26 which is secured to the angle bar 27 of the door frame, causing the strip to be flattened and pressed against the plate along 40 a wide contact area. Strip 23 extends the full width of the door section and since each section is provided with one of these strips and the edges of adjacent sections abut when the door is closed, the construction provides 45 a substantially continuous water tight joint between the top of the door and the door frame.

A similar joint is provided between the edges of adjacent sections. Fig. 6 illustrates 50 the joint between sections A' and B', it being understood that a joint of identical construction is provided between the sections A and B. As in the construction already described, the joint comprises a soft rubber strip 23' 55 folded over longitudinally and having its overlapped edges secured to a flange of the door section. In this case, the flange is at the side of section B' and the overlapped edges of the strip are secured thereto by a 60 backing strip 24' and screws 25' which pass through the flange, overlapped edges and backing strip. In this construction the backing strip 24' is longitudinally bent inwardly 65 away from the flange to form a flaring space to which the rubber strip is forced to conform

when pressed against a rigid abutment on the adjacent flange of section A', thereby effecting a wider contact surface between the abutment and rubber strip than would be the case were the back strip simply a narrow flat 70 strip. The abutment referred to consists of the flange 29 of an angle bar secured by rivets 30 to the flange of door section A'.

Fig. 5 shows a section through door section B' and the side bar 11 of the door frame, 75 illustrating the joint between these parts. It will be seen that the flange of section B' carries a rubber strip 23'' secured thereto by a backing strip 24'' and screws 25'', the construction in this respect being substantially 80 identical with that shown in Fig. 6. The strip 23'', it will be observed, is adapted to be pressed against the frame bar 11 along a wide contact surface when the section B' is in closed position. It will be understood of course that an exactly similar joint will be provided between the edge of section B and the other frame bar 11.

The meeting edges of sections A and A' are provided with a water-tight joint of the 90 construction shown in Fig. 4, which shows the joint in horizontal section. As illustrated the overlapped edges of rubber strip 23''' are secured between the flange of section A' and a backing strip 24''' by screws 25''' and 95 the strip is adapted to be compressed between this backing strip and the flange 31 of an angle bar riveted to the flange of section A. As the free edges of sections A and A' move in almost parallel directions when approaching closed position, the flange 31 is substantially parallel to the inwardly bent portion 24''' of the backing strip when the door is closed, thus effecting a maximum contact surface between the rubber strip, the flange 100 31 and the backing strip.

From the foregoing it will be clear that the invention effects a sheet metal door construction in which all joints are rendered water tight by a very simple and inexpensive construction, that is, all joints through which there is a possibility of leakage. The joint between the bottom edge of the door and the door sill is not required to be strictly watertight as there is no tendency to leakage there-through, it being observed that the container is always in upright position.

Locking mechanism is preferably provided for each of the door sections and this mechanism is so constructed and arranged that it 110 is first necessary to unlock and open one of the center sections before it is possible to unlock the remaining sections. Thus, the sections B, B' and A' carry bolts 32, one at the top and one at the bottom. These bolts are 115 mounted for vertical reciprocation in guides secured in the hollow sections. The bolts carried by sections B and B' are mounted in spaced guides 33 and 34. The guides 33 are 120 specially formed to provide reinforcements 130

for the walls of the hollow section where the hinge leaves are secured. Fig. 7 shows one of these guides in side elevation and Fig. 9 shows a horizontal transverse section through the guide. It will be observed that the guide is in the form of a yoke disposed with its edges abutting the walls 16 and 19 and with its body riveted at 36 to the wall 22 and with its arms spanning the space between walls 17 and 22. This member is formed with four apertures through which extend rivets 35, these rivets also passing through the hinge leaf. A similar reinforcing member is secured in the hollow sections opposite each leaf of the hinges, although of course where there are no bolts these members will not be provided with guiding apertures. Guide 34 has a vertical flange riveted to the inner wall 16 of the door section and a horizontal flange riveted to the end wall 17. Bolts 32 on the center section A' are guided at their inner ends by a simple apertured angle plate 33', as there is no hinge leaf at these points. The bolts are reciprocable in vertically alined holes of the spaced guides and have tapered outer ends which project through the end walls of the door sections and are adapted to enter sockets, or apertures in the top and bottom frame bars. These bolts 32 are adapted 30 to be manipulated by handles 37 projecting laterally through B slots 38 formed in the walls 17. It will be observed that these slots provide horizontal seats 39 and 39' for handles 37. Thus when a lower bolt is down in 35 locked position handle 37 occupies the position shown in full lines, Fig. 10 and the abutment or seat 39 tends to prevent it from being jarred upwardly out of locking position. When it is desired to unlock the bolt, handle 37 is turned to the left, Fig. 10, then raised 40 through the narrow portion of the slot and turned to the right and allowed to seat on abutment 39'. It will be observed that all of the bolts 32 are accessible only from the inside of the container, so that in order to unlock these bolts, which are carried on all of the sections, except section A, it is first necessary to open the latter section.

Section A, therefore, is provided with locking mechanism operable from the outside of the container. This mechanism comprises upper and lower bolts 40 mounted for reciprocation in spaced guides 41 and 42 which are secured between the inner and outer walls 16 and 19. Bolts 40 are pivoted to links 43 which in turn are pivoted to a rotatable member 44 comprising spaced discs carrying diametrical pins on which the links are pivoted. These discs are provided with a stem 45 which 50 projects through the wall of the door section, being rotatable in a horizontal bearing formed in a reinforcing plate 46 riveted to the outside of the door section. Secured to the outer end of stem 45 is an arm 47 and hinged to this arm at 49 is a hasp 48 which is bent as shown

in Fig. 8 to lie within the door panel and is slotted to receive a staple member 50 riveted on section A'. The staple member 50 is formed with two apertures adapted respectively to receive a padlock bolt 51 and a seal. 70

The construction above described provides a sectional folding door in which the sections are of hollow sheet metal construction in which the locking bolts are completely housed. The door when in closed position presents a smooth plane inner face interrupted by narrow vertical inwardly opening pockets where the flanged edges of the sections abut each other and the side frame bars. The flanged edges of the sections carry packing means disposed in these pockets and the handles for operating bolts 32 also extend therein where they are out of the way of the lading, as these pockets are so narrow that there is no possibility of any part of the lading entering them. This feature of the invention is important as it precludes the possibility of damaging valuable merchandise by sharp edges or projections of the door and its operating and locking mechanism. The present 80 construction also provides a very simple and effective door locking and operating mechanism as well as an efficient and inexpensive packing for rendering the door weatherproof, as will be obvious from the foregoing description. 95

Now having fully described my invention what I claim as new and desire to secure by Letters Patent of the United States is:—

1. A sheet metal container of the kind described having a side door opening defined by metal bars forming the door frame, a double door composed of two leaves hinged to the sides of the door frame, each leaf comprising a pair of sections foldable on an axis parallel to the axes of the hinges, vertically reciprocable locking bolts mounted on each section adapted to engage the door frame and lock the sections in closed position, means accessible from the outside of the container for operating the bolts of one of the center sections, and means accessible only from the inside of the container for operating the bolts of the remaining sections. 100 105 110

2. A sheet metal container of the kind described having a door opening defined by metal bars forming the top, bottom and sides of the door frame, a double door hinged to the sides of the door frame on vertical axes, each leaf consisting of a pair of sections foldable on a vertical axis, the edges of the center sections meeting along the vertical center line of the door opening when the sections are in closed position, a pair of upper and lower vertically reciprocable bolts mounted on the inner side of each section adapted respectively to engage the top and bottom bars to lock the sections, a lever supported on the outside of one of the center sections and operably connected with the bolts mounted on the inner 115 120 125 130

sides thereof, means for locking the lever, and means for operating the bolts of the remaining sections operable only from the inside of the container.

5. 3. A sheet metal container of the kind described having a side door opening, a double door composed of two leaves respectively hinged to the sides of the door frame, each leaf comprising two sections foldable on an axis 10 parallel to the axis of the hinges, each section being formed of an inner member of sheet metal having a vertically elongated rectangular shallow trough-like form and an outer rectangular sheet secured over said member 15 and projecting from the sides, top and bottom thereof to form a flange, and vertically reciprocable locking bolts housed in said sections and projecting through the end walls thereof for engagement with the door frame.
20. 4. A sheet metal container of the kind described having a side door opening defined by angle bars constituting the sides, top and bottom of the door frame, a double door composed of two leaves respectively hinged to the sides of said frame, each leaf being composed of side and center sections hinged together so that the center section can be turned outwardly on an axis parallel to the hinge axis so as to lie against the side section, each 25 section being constructed of an inner member of rectangular shallow trough-like form completely bordered by a flange and an outer rectangular sheet having its edges bent over said flange, vertically reciprocable locking bolts housed within each section and projecting through the end walls of the sections for engagement with the door frame, a lever on the outside of one of the center sections and operably connected to the bolts housed therein, the bolts of the remaining sections having lateral arms projecting through slots in the side walls of the sections so as to be operable only from the inside of the container.
40. 5. A container of the kind described having a door opening, a double door composed of two leaves hinged respectively to the sides of the door opening, each leaf comprising a pair of sections foldable on an axis parallel to the hinge axis, the two sections which are hinged to the door frame being substantially wider than their companion sections and all of the sections being rotatable outwardly so that the inner faces of the narrower sections can be brought against the sides of the container.
55. 6. A container of the kind described having a door opening defined by top, bottom and side bars constituting the door frame, a double door composed of two leaves, hinges by which the leaves are swung on the door frame, each of said hinges consisting of two members secured respectively to the frame and leaf and a connecting member pivoted to said members on parallel axes, each of said leaves being composed of two sections foldable on an axis parallel to said axes, all of said

sections being rotatable outwardly so that the leaves may be folded and then swung on said hinges to bring the inner faces of the center leaf sections against the side of the container.

7. A container of the kind described having a door opening defined by metal bars forming the top, bottom and sides of the door frame, a double door composed of two leaves, hinges by which the leaves are swung on the sides of the door frame, each of said hinges consisting of two members secured respectively to the frame and leaf and a connecting member pivoted to said members on parallel spaced axes, the leaf sections which are hinged to the door frame being substantially wider than their companion sections, all of said sections being rotatable outwardly so that the leaves may be folded and then swung to bring the inner faces of the narrower sections against the side of the container.

8. A sheet metal container of the kind described having a side door opening defined by metal bars forming the top, bottom and sides of the door frame, a double door composed of two leaves respectively hinged to the sides of said frame, each leaf comprising a pair of sections foldable on an axis parallel to the hinge axis, each section being of hollow sheet metal construction and having an elongated rectangular form presenting a plane inner face and a bordering flange substantially coplanar with its outer face, locking bolts for the sections reciprocably mounted on the interior thereof and projecting through the end walls of the sections for engagement with the door frame, a shaft projecting through the outer face of one of the center sections and operably connected to the locking bolts of said section, an arm secured to the outer end of said shaft, means for operating said arm when the bolts of said center section are in locking position, the bolts of the remaining sections having laterally extending arms projecting through slots in the side walls of the sections and accessible only after said center section has been opened.

9. In a door for containers of the kind described, a door section of elongated rectangular form having a hollow sheet metal construction presenting a plane inner face and a bordering flange substantially coplanar with its outer face, upper and lower reciprocable bolts mounted on the interior of said section projecting respectively through the top and bottom walls of said section for engagement with the door frame, a side wall of said section being formed with slots and said bolts having lateral arms extending through said slots, the latter presenting seats upon which said arms may rest to support the bolts.

10. In a door for containers of the kind described, a door section of elongated rectangular form having a hollow sheet metal construction presenting a plane inner face

- and a bordering flange substantially coplanar with its outer face, a hinge member on the outer face of said section adjacent an edge thereof, a reinforcing guide on the interior of said section, fastening devices 5 passing through the hinge member and said guide, and a locking bolt reciprocable and rotatable in said guide projecting through an end wall thereof for engagement with the door frame and having a laterally projecting arm extending through a slot in a side wall of said section.
11. In a door for containers of the kind described, a leaf composed of two sections 15 foldable on an axis parallel to the hinge axis of the door, each section being of elongated rectangular form and having a hollow sheet metal construction presenting a plane inner face and a bordering flange substantially coplanar with its outer face, a soft 20 rubber strip folded and having its overlapped edges extending along the inner face of one of the side flanges of a section, a metal backing strip secured over said edges by fastening bolts passing through the flange, edges 25 and strip, said strip being bent inwardly away from the flange, and an angle bar secured to the inner face of the adjacent flange of the companion section adapted to be 30 pressed against the rubber strip when the door is closed.
12. In a door for containers of the kind described, a door section of elongated rectangular form having a hollow sheet metal construction presenting a plane inner face and a bordering flange substantially coplanar with its outer face, a soft rubber strip folded and having its overlapped edges extending throughout the length of one of the side flanges of the section on the inner face thereof, a metal backing strip over said edges, fastening devices passing through said flange, edges and strip, said backing strip being bent inwardly away from the flange.
13. In a door for containers of the kind described, a door section of elongated rectangular form having a hollow sheet metal construction presenting a plane inner face and a bordering flange substantially coplanar with its outer face, a resilient packing strip 45 extending throughout the length of one of the side flanges of the section on the inner face thereof, a backing strip for said packing strip, and fastening devices passing through said flange and strips, said backing strip being bent inwardly away from the flange along a longitudinal line.
14. In a sheet metal container of the kind described having a side door opening defined by metal bars forming the top, bottom and sides of the door frame, a double door composed of two leaves respectively hinged to the sides of said frame, each leaf comprising a plurality of sections foldable on axes 50 parallel to the hinge axes, each section having a vertically elongated rectangular form and being of hollow sheet metal construction presenting a plane inner face and a bordering flange substantially coplanar with its outer face, and yieldable packing strips secured to the inner faces of the top flanges of said sections adapted to cooperate with the top frame bar to form a water tight joint.
15. In a sheet metal container of the kind described having a side door opening defined by metal bars forming the top, bottom and sides of the door frame, a double door composed of two leaves respectively hinged to the sides of said frame, each leaf comprising a plurality of sections foldable on axes parallel to the hinge axes, each section having a vertically elongated rectangular form and being of hollow sheet metal construction presenting a plane inner face and a bordering flange substantially coplanar with its outer face, and means secured to the inner faces of the top and lateral flanges of the sections for effecting weatherproof joints when the door is closed.
- In testimony whereof I hereunto affix my 90 signature.
- FREDERICK K. FILDES.
